CLAIM

The ornamental design for a display screen or portion thereof with graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is a front view of a display screen or portion thereof with graphical user interface showing the claimed design.

The outermost broken lines in the FIGURE show a display screen or portion thereof, and form no part of the claimed design. The other broken lines in the FIGURE show portions of the graphical user interface that form no part of the claimed design.

**1 Claim, 1 Drawing Sheet
(1 of 1 Drawing Sheet(s) Filed in Color)**

Diagram illustrating the relationship between **Product** and **Customer** through **Order** and **OrderLine**.

```

    graph TD
        Product[Product] --> Order[Order]
        Product --> OrderLine[OrderLine]
        Order --> OrderLine
        Order --> Customer[Customer]
        OrderLine --> Order
        OrderLine --> Product
        OrderLine --> Customer
    
```

Product (Root Node):

- Properties: Name, Description, Price, Availability, Type, Manufacturer, Workshops, Performance.
- Relationships: Order, OrderLine.

Customer (Leaf Node):

- Properties: Name, Address, Contact, Email, Phone.
- Relationships: Order.

Order (Leaf Node):

- Properties: OrderID, OrderDate, OrderStatus, OrderType, OrderValue.
- Relationships: Customer, Product, OrderLine.

OrderLine (Leaf Node):

- Properties: OrderLineID, ProductID, Quantity, UnitPrice.
- Relationships: Order, Product.
